[57] CLAIM

The ornamental design for a lamp socket, as shown and described.

DESCRIPTION

FIG. 1 is a front elevational view of a lamp socket showing my new design, the rear elevational view thereof being identical;

FIG. 2 is a left side elevational view thereof, the right side elevational view thereof being identical;

FIG. 3 is a top plan view thereof;

FIG. 4 is a bottom plan view thereof;

FIG. 5 is a front elevational view of a lamp socket showing a second embodiment of my new design, the rear elevational view thereof being identical;

FIG. 6 is a left side elevational view thereof, the right side elevational view thereof being identical;

FIG. 7 is a top plan view thereof;

FIG. 8 is a bottom plan view thereof;

FIG. 9 is a front elevational view of a lamp socket showing a third embodiment of my new design, the rear elevational view thereof being identical;

FIG. 10 is a left side elevational view thereof, the right side elevational view thereof being identical;

FIG. 11 is a top plan view thereof;

FIG. 12 is a bottom plan view thereof;

FIG. 13 is a front elevational view of a lamp socket showing a fourth embodiment of my new design, the rear elevational view thereof being identical;

FIG. 14 is a left side elevational view thereof, the right side elevational view thereof being identical;

FIG. 15 is a top plan view thereof;

FIG. 16 is a bottom plan view thereof;

FIG. 17 is a front upper right perspective view of the embodiment of FIG. 1; and,

FIG. 18 is a rear lower left perspective view thereof.
